UNITED STATES PATENT OFFICE.

ARTHUR E. LAVALLEE, OF LOS ANGELES, CALIFORNIA.

RACK FOR PAPER ROLLS.

Application filed December 4, 1922. Serial No. 604,757.

To all whom it may concern:

Be it known that I, ARTHUR E. LAVALLEE, a citizen of the United States, residing at Los Angeles, in the county of Los Angeles 5 and State of California, have invented a new and useful Rack for Paper Rolls, of which the following is a specification.

This invention relates to a holder or rack for supporting a roll of paper, such as used 10 in shops, and particularly tailor shops. As usually constructed these racks embody a wooden base with standards at the ends thereof for supporting the roll. It is usually necessary to bolt the base to the 15 counter or shelf on which the rack stands.

The general object of the present invention is to produce a very simple and inexpensive rack for supporting a paper roll which will operate effectively to permit the 20 paper to be drawn from the roll and torn off at any point desired; also to provide a construction which will operate to insure sufficient pressure of the tearing blade upon the face of the roll, at the same time enabling the springs to be substantially 25 concealed from view; also to improve the general construction of racks of this kind, and to provide simple means for enabling the rack to hold itself fixed upon the counter 30 when the paper is torn off without necessitating the use of fastening bolts or screws securing the base to the counter.

Further objects of the invention will appear hereinafter.

35 The invention consists in the novel parts and combination of parts to be described hereinafter, all of which contribute to produce an efficient rack for paper rolls.

A preferred embodiment of the invention 40 is described in the following specification while the broad scope of the invention is pointed out in the appended claims.

In the drawing—

45 Figure 1 is a front elevation of a rack embodying my invention showing a portion of a counter upon which the rack rests, parts of the counter being shown in section to illustrate details of the invention.

50 Fig. 2 is an end elevation and shows the rack as viewed from the right end as shown in Figure 1; this view also shows a portion of the counter broken away, and like Figure 1 indicates the paper roll in place.

55 Fig. 3 is a vertical cross section taken on the line 3—3 of Figure 1 and passing through the counter which is broken away

but in this view the paper roll itself is omitted.

Fig. 4 is a plan of the rack with the 60 paper roll omitted.

Fig. 5 is a horizontal section taken about on the line 5—5 of Figure 2 but this view is upon an enlarged scale with certain parts broken away; it particularly illustrates details which I may employ at the point where 65 the arms of the tearing blade are secured to the frame.

Fig. 6 is a detail and is a section taken about on the line 6—6, Figure 5, showing a portion of one of the arms of the tearing 70 blade, particularly illustrating the connection of the spring to the arm.

Fig. 7 is a horizontal section taken across the arm about at the point 7—7 of Figure 6 but also illustrating the tearing blade broken 75 away; this view further illustrates the connection of the spring with the arm.

Fig. 8 is a plan upon a greatly reduced scale and illustrates a form of blank which I may employ in producing the frame of 80 the rack.

In practicing my invention I prefer to construct the frame 1 of the rack of sheet metal comprising a base plate 2 with integral upwardly extending standards 3 which are formed by bending up the ends of a plate or blank 4 such as illustrated in Figure 8. This plate constitutes, of itself, the base for the rack. The upper ends of the standards 3 are connected together by a horizontal tie 85 bar 5 which extends longitudinally with the frame. This tie bar is also sheet metal or bar metal and I prefer to connect it to the upper ends of the standards by welding. The standards are provided with any suitable means for supporting a paper roll 6. This means may consist of two inclined slots 7 (see Fig. 2).

In order to enable the paper to be torn off at any point desired I provide a tearing 100 blade 8 which extends longitudinally toward the frame and this blade has an arm 9 at each end which lies adjacent to its corresponding standard 3. I provide suitable means for pivotally supporting each arm on the frame and provide spring means for pressing the blade against the face of the roll. In order to accomplish this I provide a spring casing 10 supported on the frame and preferably mounted on the upper side 105 of the tie bar 5.

Under the spring casing 10 the tie bar 5 is

formed into an enlarged head 11, see Figure 4, and the casing 10 is provided with laterally extending wings 12 located so as to overlie this head 11, and these wings are secured

5 to the enlarged head 11 by suitable fastenings such as rivets or bolts 13. The inner end of the spring casing is provided with a projecting foot 14 which is also attached by a bolt 15 to the bar. Within the spring casing or barrel 10 I provide a pivot member or pivot screw 16 which has a thread connection 17 with the wall of the casing at its inner end, and this screw passes through and pivotally attaches the arm 9 to the 10 end of the casing. Within the casing and around the pivot screw 16 I provide a coil spring 18, the axis of which extends longitudinally with the bar; the inner end of this spring is fixed by any suitable means within the casing and the outer end of the spring is bent into a shank 19 which engages the adjacent arm 9 so that the spring will exert its force to press the blade 8 against the side of the roll. In making this connection I prefer 15 to provide a socket for the shank 19 which may be in the form of a small bent tube 20 which is welded or brazed into the angle 21, (see Figure 7), which is formed between the web 22 and flange 23 of the arm.

20 In order to strengthen the standards they have laterally enlarged lower ends 24 at the point where they unite integrally with the base or base plate 2. In forming the blank 4, the body of the blank is provided with a 25 tongue 4^a at each end and these tongues are bent up to form the standards. In order to facilitate the welding of the tie bar 5 to the upper ends of the standards each tongue 4^a is provided with a reduced tip 4^b which 30 provides metal to weld into the end of the bar. In this connection attention is called to the fact that the spring casing 10 extends over the welded joint and operates to increase the strength of the construction at 35 this point.

40 In order to give the base 2 an ornamental appearance and also to make it lighter I provide it with openings such as the openings 25 which are punched through it when the blank is formed.

45 By reason of the fact that this rack is constructed of sheet metal it will be relatively light, and when paper has been used to a large extent from the roll the total weight of the roll and rack will be small and hence when the paper is pulled there might be a tendency for the base 2 to slide on the counter 26 which supports the base. In order to overcome this tendency and prevent the 50 rack from slipping, without employing bolts I simply provide the base plate 2 at each end with a small downwardly projecting pin or spur 27. If desired the base may be pressed down so as to cause these spurs 27 to engage its upper face, see Figure 1, but if desired

they may be simply permitted to rest upon the upper face of the counter; in this case their points will operate to prevent the base from slipping.

55 I also prefer to make the base 2 relatively wide so that the tension on the paper in pulling it off the roll cannot possibly overturn the rack by tilting it up on its forward edge as a fulcrum.

60 It is understood that the embodiment of the invention described herein is only one of the many embodiments this invention may take and I do not wish to be limited in the practice of my invention nor in my claims to the particular embodiment set forth.

65 I claim:

1. In a rack for supporting a roll of paper, the combination of a frame consisting of a relatively wide base plate constituting the base for the rack, and having integral upwardly extending standards at its ends, means for supporting the paper roll between the standards, a tie-bar connecting the upper ends of the standards, a blade extending longitudinally of the frame and having an arm at each end thereof, a spring casing supported on the end of the tie bar, a coil spring held in the casing, a pivot-screw pivotally supporting each arm, a spring within the casing engaging one of the arms and operating to press the blade against the face of the paper roll.

2. In a rack for supporting a roll of paper, the combination of a frame consisting of a base plate constituting the base for the rack, and having integral upwardly extending standards at its ends, means for supporting the paper roll between the standards, a tie-bar connecting the upper ends of the standards, a blade extending longitudinally of the frame and having an arm at each end thereof, a spring casing mounted on the upper side of the tie-bar at each end thereof, a pivot-screw pivotally supporting each arm, extending longitudinally within its corresponding spring casing and having a thread connection with the inner end of the casing, a coil spring disposed within each casing and around its corresponding pivot-screw, and means for attaching the outer ends of each of the springs to its corresponding arm to enable the springs to press the blade against the face of the paper roll.

3. In a rack for supporting a roll of paper, the combination of a frame having a relatively wide metal plate constituting the base of the rack, having a standard at each end, a tie-bar connecting the upper ends of the standards and having a laterally enlarged head at the point of attachment to the standards, a blade extending longitudinally with the frame and having an arm at each end lying adjacent to its corresponding standard, a spring casing corresponding to

each arm supported on the adjacent end of the tie-bar having laterally projecting wings resting on the enlarged head of the tie-bar and secured thereto, a pivot member extending longitudinally in the spring casing and pivotally securing the arm to the end of the casing, and a coil spring disposed around the pivot member within the casing with its end connected with the arm to press the blade against the face of the roll. ¹⁰

Signed at Los Angeles, California, this 25 day of November 1922.

ARTHUR E. LAVALLEE.
